UNITED STATES PATENT OFFICE.

JEROME L. RICHARDSON, OF RED OAK, IOWA.

ACETYLENE-GENERATOR.

1,025,160.

Specification of Letters Patent.

Patented May 7, 1912.

Application filed April 27, 1911. Serial No. 623,641.

To all whom it may concern:

Be it known that I, JEROME L. RICHARDSON, a citizen of the United States, residing at Red Oak, in the county of Montgomery and State of Iowa, have invented certain new and useful Improvements in Acetylene-Generators, of which the following is a specification, reference being had therein to the accompanying drawing.

10 This invention relates to apparatus for generating acetylene gas, and has special reference to that type of acetylene gas generator in which a vertically movable bell is employed together with means for gradually 15 submerging carbid into water to generate and collect the gas within said bell.

The invention has for its object to provide an improved acetylene gas generator which will be simple in construction and effective 20 in operation and may be readily removed for repair and charged with carbid and which will avoid any danger of explosion.

Referring to the accompanying drawings: Figure 1 is a view in vertical section of an 25 acetylene gas generator constructed in accordance with this invention and shown as sunk in the ground. Fig. 2 is an elongated detail view in vertical section of a portion of the apparatus consisting of a carbid 30 holder which is removably mounted in the gas bell. Fig. 3 is an enlarged detail view in vertical section of a portion of the carbid holder. Fig. 4 is a detail plan view of one 35 of a number of disks employed with a carbid holder. Fig. 5 is an enlarged detail view of a metallic blank used to form the angular perforated metallic strip shown in Fig. 6. Fig. 6 is a detail view of an angular perforated metallic strip serving as 40 a water conduit for the carbid holder. Fig. 7 is an enlarged detail view of a portion of the end of a gas pipe located in the end of a gas pipe shown in vertical section.

In the construction of this invention a 45 metallic tank 1 of suitable size is employed which is sunk in the ground as shown in Fig. 1, and is provided with a solid bottom 2. Located in the tank 1 is a vertically movable bell 3 having at its upper end laterally projecting arms 4, each of said arms having on its outer end a friction roller 5 which bears against the inside of the tank 1, the arms 4 and friction rollers 5 serving to steady the bell 3 when it is raised and lowered. Suspended within the bell 3 is a 50 cylindrical metallic casing 6 open at its

lower end and having a closed top 7 with an annular flange 8 which is adapted to be seated in the shoulder of an opening in the top of the bell 3, through which opening 60 the casing 6 is adapted to be removed. The casing 6 is of a length equal to that of the bell 3 and is for the purpose of containing carbid. The casing 6 is secured in place by any suitable means, as, for example, by nuts 65 and bolts 9. Extending centrally through the casing 6 and projecting through its top 7 is a pipe 10 which is held in place by means of a transverse bar 11 through which the pipe 10 projects, and is clamped in place 70 thereon by nuts 12. The bent outer ends 13 of the bar 11 rest on the top of the bell 3. Located at intervals apart on the pipe 10 and removable therefrom are perforated disks 14 which are slidably removable from 75 the pipe 10 and are held in spaced relation to each other by any suitable means, as, for example, by short tubes 15 mounted on the tube 10 and having a flanged lower end 16 resting on the next lower disk 14. The 80 lower end of the casing 6 is provided with a chambered portion 16' having a lower open end and located in said chamber 16' and slidably and detachably mounted on the pipe 10 is a cone shaped float 17. It aids 85 in lifting the carbid holder and bell.

Mounted in the sides of the casing 6 are a number of vertical perforated conduits 18 of any suitable shape for the passage of water, and, as here shown, preferably of an 90 angular shape formed by bending a metallic blank strip 19, as shown in Fig. 5 into the angular shape shown in Fig. 6 with the sides 20 having apertures 21. These perforated conduits 18 are secured in any suitable manner to the inner sides of the casing 6 and the disks 14 are seated over said conduits 18 by means of notches 22 in the periphery of each disk. These perforated conduits 18 are for the purpose of conducting 95 water to the carbid and also for the passage of the generated gas to the tube 10 which is provided at its upper end with a number of apertures or perforations 23 through which the generated gas passes down through the 100 tube 10. The lower end of the tube 10 has projecting into the same the upper end of a pipe 24 provided with a perforated cap 25, and the lower end of the pipe 24 is connected by an elbow joint 26 with a pipe coupling joint 27 containing a cock or valve. The 105 other elbow pipe 28 of the coupling joint has 110

seated therein the lower end of a vertical pipe 29 the upper open end of which projects up into the bell 3. The cock in the coupling joint 27 is connected with an operating rod 5 which extends up through a pipe 31 suspended from the top of the bell and provided with a handle 32 by means of which said valve is operated. The object of this 10 valve is to shut off the gas in the bell so that it will not escape when the carbid holder is removed from the bell. The gas located in the bell 3 is admitted to the desired point for use by means of a vertical pipe 33 having its open upper end projecting into the bell and its 15 lower end coupled to a horizontal short pipe 34 which in turn is coupled to a vertical pipe 35 projecting out of the top of the casing 1 and connected by a short pipe 36 with a pipe coupling 37 containing a stop cock 20 38, said coupling being connected to a pipe 39 leading to a place where the gas is to be used.

Located at the bottom of the casing 6 and passing through its wall is a U-shaped tube 25 40 extending up on each side of the wall of the casing and secured thereto in any suitable manner. The tube 40 serves to prevent the escape of gas while the apparatus is being charged, being of a sufficient length to 30 be submerged in the water and thus making a water seal just before the carbid touches the water and begins to generate gas, and, as hereinafter more fully set forth, also serves to permit the escape of all the air 35 through the lower end of the casing 6 while the carbid holder is being replaced after being recharged, the gas bell lying flat on the water thus forcing all of the air out before the upper end of the tube 40 is submerged 40 so as to fill with water.

The carbid casing 6 is charged with carbid by removing it from the bell and inverting the same. The float 17 and the disks 14 with their supporting tubes 15 are removed from the pipe 10 and each chamber formed by the disks 14 as they are replaced is filled with carbid 41. After the carbid holder has been charged, as aforesaid, it is replaced in the bell and the latter 50 is lowered into the water 42 in the tank 1. In charging the water the gas bell 3 lies flat on the water, and the pipes 29 and 33 telescope into pipes 43 depending from the top of the bell, thereby leaving the bell or 55 carbid holder entirely free from air. As soon as the carbid casing charged with carbid strikes the water the pressure is created in the carbid holder and as it is forced down to the proper position the air is expelled through the tube 40 and just before the carbid at the lower end of the carbid holder comes in contact with the water and begins to make gas, the tube 40 fills the 60 water, making a gas tight seal, as shown in 65 Fig. 3, and starts the machine in operation

and practically no air can be drawn out of the pipes or mixed with the gas. By placing the carbid on a series of perforated shelves the whole charge of carbid is prevented from being moistened at once, and the necessity 70 for feeding the carbid to the water is avoided, and, moreover, the caking of the residuum or refuse carbid is avoided and the spaces between the several charges of carbid assist in preventing an over supply of 75 gas and make it unnecessary to change the water so frequently for the reason that all of the residuum of the carbid is retained in the holder, from which it is readily removed before recharging.

By means of the foregoing construction the machine may readily be recharged while in operation, the service being continuous without a sufficient amount of air being mixed with the gas to materially affect the 85 brilliancy of the light. By means of this construction also in cutting off the gas described in connection with the handle 32 the carbid holder can be removed for recharging the machine without turning out 90 the lights. It will readily be seen that as the carbid holder is lowered into the water the latter will pass through the perforated conduits 18 and is distributed among the carbid gradually as the carbid holder is 95 lowered the generated gas passing down through the tube 10 and out of the tube 29 into the bell.

What I claim is:—

1. In an acetylene gas generator of the 100 kind described, a carbid holder consisting of a cylindrical casing with a closed top and an open lower end, and a chamber in the lower end of said casing, a central gas tube extending through said casing, and having an open 105 lower end, and an apertured upper end communicating with said casing, a column of perforated disks detachably mounted on said tube and spaced apart from each other, and a U-shaped tube mounted in the side 110 of the lower end of said carbid holder with its upper end in a plane below the lower end of the column of perforated disks, and serving to form a water seal therefor.

2. In an acetylene gas generator of the 115 kind described, a water tank, a bell vertically movable in said water tank, a carbid holder consisting of a cylindrical casing suspended from the top of said bell, and having a central gas tube, a number of removable 120 perforated disks mounted thereon and spaced apart from each other, a number of vertical conduits having perforations and located on the inner side of said holder and extending through said disks, a U-shaped gas 125 pipe having one arm projecting up into the end of said pipe in the carbid holder and at its other end opening into said carbid holder, a valve located between said arms in 130 said pipe, and an operating rod connected

with said valve and projecting through the top of said bell.

3. In an acetylene gas generator of the kind described, a water tank, a bell vertically movable in said water tank, and having tubes depending from its top inside thereof, and an opening in its top, a carbide holder depending within said bell and detachably mounted in said opening in its top, and having a central gas tube extending from top to bottom of said holder and open at its lower end and having apertures at its upper end opening into said holder, a number of perforated disks slidably and detachably mounted on said pipe, and spaced apart from each other, tubes on said pipe located between said disks, angular perforated conduits located on the inner sides of said holder, the lower end of said holder being formed with a chamber, a cone shaped support detachably mounted on said pipe in

said chamber, a U-shaped pipe mounted on one side of said chamber and serving as a water seal, a U-shaped pipe located in the lower end of said water tank and having one arm projecting into said pipe in the carbide holder and its other arm opening into the bell, a discharge pipe projecting into the lower end of said bell, a vertical pipe connected with said discharge pipe and projecting through the top of the water tank, and a pipe leading to the point of discharge connected with said vertical pipe, the vertical pipes projecting into the bell being adapted to telescope with the pipes depending from the top of the bell.

In testimony whereof I hereunto affix my signature in presence of two witnesses.

JEROME L. RICHARDSON.
